UNITED STATES PATENT OFFICE.

GEORGE W. LA VOO, OF STEUBENVILLE, OHIO.

PIPE-THREADING MACHINE.

1,126,792.

Specification of Letters Patent.

Patented Feb. 2, 1915.

Application filed November 15, 1913. Serial No. 801,138.

To all whom it may concern:

Be it known that I, GEORGE W. LA VOO, a citizen of the United States, residing at Steubenville, in the county of Jefferson and State of Ohio, have invented new and useful Improvements in Pipe-Threading Machines, of which the following is a specification.

My invention relates to machines for threading metal pipe.

10 The objects of my invention are to provide means whereby the pipe, at the conclusion of the threading operation, automatically opens the scroll; to provide a spring-operated latch for releasing the scroll, the 15 latch being tripped by the pipe when the threading thereof is finished; and to facilitate the removal and insertion of the threading dies.

Other objects will appear hereinafter.

20 Referring to the accompanying drawings, Figure 1 is partly a side elevation and partly a vertical central longitudinal section of a machine embodying my invention; Fig. 2, an end elevation of Fig. 1; Fig. 3, a 25 top plan view thereof; Fig. 4, a similar view of a portion of Fig. 3 with the parts in a different position; Fig. 5, an elevation of the threading head and the scroll therefor; Fig. 6, a perspective view of the 30 scroll-locking and releasing catch; Fig. 7, a perspective view of the reamer; Fig. 8, a side view of the sleeve for holding the reamer and the trip-bar for the said latch; Fig. 9, an end view of Fig. 8; and Fig. 10, 35 a perspective view of the said trip-bar.

On the drawings, 1 represents the table on which the fixed support 2 for the rotary chuck 3 is mounted.

4 The drive-wheel for rotating the chuck, 40 to which wheel suitable power may be connected.

5 is a carriage caused to slide on the table 1 by means of the hand lever 6, connected to the table 1 by the pivot or fulcrum pin 7. The lever 6 is pivotally connected by the link 8 to the lower end of the lever 9, having its upper end pivoted to the carriage 5 by the pin 10 and its intermediate portion to the table by the pin 11. 50 The carriage 5 supports the head 12, which in turn supports the die-head 13 and various other parts to be presently described. The die-head has on its rear face the axially arranged boss 14 provided with 55 the grooves 15. The front face of the head

12 has the horizontal recess 16 with its forward end provided with the flanges 17 extending inwardly from the upper and lower edges thereof. The boss 14 is slid laterally in the said recess with the flanges 17 in 60 the grooves 15 until the axial opening in the head 13 is in alignment with the opening 18 in the head 12. As shown on Fig. 1, the boss fits loosely in the recess as also do the flanges 17 in the said grooves so 65 that the head 13 may float or move slightly in any direction transversely of the axis of the head 13 or of the pipe 48 to be threaded to accommodate itself to slight irregularities in the ends of the pipes during 70 the threading operation.

The sleeve or barrel 19 is held in the opening 18 by means of the set-screw 20 (Fig. 2) working in the nut 21 and having its inner end in engagement with the sleeve 75 or barrel. The forward end of the sleeve is flush with the bottom of the recess 16 so that it will not interfere with the sliding of the boss 14 for removing the head 13 from the head 12.

The die-carriers 23 swing laterally on the pivot 24 carried by the lower portion of the die-head 13. These carriers have their opposing faces intermediate of their ends recessed to receive the end of the pipe to be threaded; and support the radially arranged threading dies 25 projecting into the said recesses, where they may engage the exterior surface of the pipe and cut threads therein. The said recesses in the die-holders form a 85 round opening in substantial alignment with the opening in the heads 12 and 13.

26 is a horizontal scroll rotatable on the center pin 27 supported by the head 13. The scroll 26 is provided with the two opposite scroll slots 28 beginning at opposite sides of the pin 27 and extending in opposite directions in a manner well-known in the art. These slots receive the vertical pins 29 extending upwardly on the top of the die-holders 23. In a manner well understood in the art the rotation of the scroll in one direction closes the die carriers and its rotation in the opposite direction opens the same. In order to allow for the herein described floating movement of the die-head 13 I have made the inner ends of the slots 28 on a radius drawn from the center of the pin 27 so that any movement of the pins 29 100 in the slots caused by the floating movement 105

110

of the die head and, therefore, of the die-carriers 23 will have no tendency to move the pins 29 outwardly and thereby partially open the threading dies.

5 30 is a horizontal sliding catch supported in the upper end of the head 12 and having its forward end in engagement with the periphery of the scroll. The scroll has in its edge the notch 31 into which the end of the 10 catch 30 is adapted to extend to prevent the rotation of the scroll in such a direction as to spread the pins 29 apart. The periphery of the scroll is provided with the annular groove 32 in which one end of the 15 spring 33 is secured, the other end of the spring being connected to the bracket 34, on the rear end of the head 12. The spring 33 is partially wound on the scroll in such a direction as to cause the scroll, when released from the catch 30, to rotate in a direction to spread the pins 29 and open the dies, the direction of rotation being indicated by the arrow on Fig. 4. The catch 30 has its rear end connected by the pivot 20 25 35 to the upstanding lever 36 which is pivoted at its lower end to the bracket 37 projecting rearwardly from the head 12.

38 is a spring connected between the upper end of the lever 36 and the post 39 on the top of the head 12, for yieldingly holding the catch 30 in constant engagement with the periphery of the scroll.

The sleeve 19 is provided with a central longitudinal rectangular opening 40 in which the reamer holder having a cross section corresponding to the shape of the opening 40 is reciprocable. The forward end of the holder 41 is provided with the removable cutter or reamer blade 42 tapered forwardly and arranged to remove the bur from the inner end of the pipe just prior to the conclusion of the threading operation. The holder 41 has its rear end resting against the spring 43 secured to the rear end 45 of the head 12, the spring holding the reamer yieldingly in working position. By this arrangement the reamer will be pushed forwardly farther in order to ream large pipes and will be moved in the opposite direction when smaller pipes are to be reamed, thereby obviating the necessity of changing reamers for every size of pipe to be reamed. The upper wall of the opening 40 is provided with the longitudinal recess 50 or groove 44 which registers with the longitudinal recess or groove 45 in the lower face of the reamer carrier 41.

46 is a trip bar shaped in cross section to fit the registering grooves 44 and 45, the said bar having its rear end resting against the adjustable screw 47 secured in the lever 36. The forward end of the bar 46 is arranged to be engaged by the end of the pipe 48 at the conclusion of the threading operation. By using the trip-bar 46, rather than

the reamer, to trip the scroll, the reamer need not be changed for every size of pipe, as would be required if the reamer tripped the scroll, because the reamer holder 41 would have different distances to travel according to the sizes of the pipe. With a large pipe the blade 12 would be positioned farther forwardly than it would with a smaller pipe. Accordingly, a large pipe would have a longer portion of its end threaded than a smaller pipe before the scroll would be released.

49 is a vertical upstanding pin on the top of the scroll 26, disposed so as to be brought against the forward end of the stop 50, 80 which I have shown in the form of an L-shaped bar secured to the rear end of the table 1.

The operation is as follows: The pipe to be threaded is secured in the chuck 3 which is then set in operation by power supplied to the gear-wheel 4. The operator moves the lever 6 so as to move the carriage 5 toward the right-hand of the pipe and cause the closed dies to slide partially over the end of the pipe. Immediately before the conclusion of the threading operation the end of the pipe engages the trip bar 46 which, through the adjusting screw 47 and the lever 36 causes the latch 30 to be withdrawn from the notch 31 in the scroll. Prior to the release of the latch from the scroll the parts are as shown on Figs. 1, 2, 3, and 5, but upon the movement of the latch 30 to the right, the spring 33 causes the scroll to move in the direction of the arrow (Fig. 4) and the scroll assumes the position shown on Fig. 4, where the pins 29 are spread apart farther than in Fig. 3. The spreading apart of the pins 29 opens the dies thereby withdrawing the dies from the threads on the pipe. The operator then moves the handle 6 so as to cause the table 5 to move to the right and in doing so causes the pin 49 on the scroll to engage the stop 50 which rotates the scroll to the left until it is again locked in the position shown on Fig. 3 by the latch 30 reengaging the notch 31. Just prior to the completing of the threading operation, the reamer 42 removes the bur from the end of the pipe, the spring 43 allowing the reamer to move slightly to the right.

I claim—

1. In a pipe threading machine, a chuck 120 for holding and rotating a pipe axially, a carriage, a plurality of threading dies supported by the carriage, a scroll for closing and opening the dies with respect to the end of the said pipe, means for feeding the dies 125 toward the pipe and backing the same away therefrom, a stop, arranged to arrest the backward movement of a portion of the scroll at one side of the axis thereof while permitting the axis of the scroll to continue 130

its backward movement, thereby causing the rotation of the scroll and the closing of the dies.

2. In a pipe threading machine, a chuck for holding and rotating a pipe axially, a carriage, a plurality of threading dies supported by the carriage, a scroll for closing and opening the dies with respect to the end of the said pipe, means for feeding the dies toward the pipe and backing the same away therefrom, a pin secured eccentrically to the scroll, and a stop arranged to arrest the backward movement of the said pin while the axis of the scroll continues its backward movement, thereby causing the rotation of the scroll and the closing of the dies.

3. In a pipe threading machine, a plurality of threading dies, a scroll for closing and opening the same, means tending to move the scroll so as to open the dies, a latch to prevent the scroll from opening the dies, a head to support the dies, a reamer in the head, having a cutting edge inclined forwardly and toward the center of the head and arranged to enter the end of the pipe and ream the interior corner of the said end, a spring for urging the reamer toward the end of the pipe, a slideable trip-bar in the head, arranged to be moved by the pipe at the close of the threading operation, and means for causing the trip-bar when so moved to release the latch from the scroll.

4. In a pipe threading machine, a plurality of threading dies, a scroll for closing and

opening the same, means tending to move the scroll so as to open the dies, a latch to prevent the scroll from opening the dies, a head to support the dies, the head having an angular opening in alignment with the pipe, a reamer therein for engaging the end of the pipe, a slideable trip-bar in a slot in the reamer and sleeve arranged to be moved by the pipe at the close of the threading operation, and means for causing the trip-bar when so moved to release the latch from the scroll.

5. In a pipe-threading machine, a plurality of die-holders pivoted at one end to swing transversely of the pipe, and having their remaining ends provided with pins in line therewith, a peripherally-notched scroll having cam-slots to receive the pins, means tending to rotate the scroll so as to move the die-holders away from each other, a latch movable in a path transverse of the axis of the scroll to enter a peripheral notch in the scroll and thereby prevent the scroll from moving the die-holders away from each other, and means controlled by the forward end of the pipe for withdrawing the latch from the said notch.

Signed at Steubenville, O., this 10th day of November, 1913.
